(57) **CLAIM**

We claim the ornamental design for a hopper assembly, as shown and described.

DESCRIPTION

FIG. 1 is a top, front, and left side perspective view of a hopper assembly showing our new design;
 FIG. 2 is a rear, bottom, and right side perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines shown in FIGS. 1-8 represent portions of the hopper assembly that form no part of the claimed design.

1 Claim, 6 Drawing Sheets
